UNITED STATES PATENT OFFICE.

JOHN HARVEY HALL, OF WELLINGTON, COLORADO.

SAFETY PARACHUTE ATTACHMENT FOR AEROPLANES.

1,303,474.

Specification of Letters Patent. Patented May 13, 1919.

Application filed November 27, 1918. Serial No. 264,370.

To all whom it may concern:

Be it known that I, JOHN HARVEY HALL, a citizen of the United States, residing at Wellington, in the county of Larimer, State 5 of Colorado, have invented a new and useful Safety Parachute Attachment for Aeroplanes; and I do hereby declare the following to be a full, clear, and exact description of the invention, such as will enable others skilled in the art to which it appertains to 10 make and use the same.

The present invention relates to a safety parachute attachment for airships, and has for its object to provide a device of this 15 character which embodies novel features of construction whereby the parachute can be collapsed and held in an out of the way position when not in use, although it can be quickly released and brought into operative 20 position in the event of a mishap to the airship.

Further objects of the invention are to provide a safety attachment of this character which does not interfere in any manner 25 with the normal operation of the air ship when the parachutes are collapsed and in inoperative position, which provides for housing the collapsed parachutes in such a manner that they do not increase the wind 30 resistance to the craft or interfere with the lifting powers of the supporting planes, and which is arranged in such a manner that it can be instantly released and brought into operative position by the aviator in the event 35 of an accident.

With these and other objects in view, the invention consists in certain novel combinations and arrangements of the parts as will 40 more fully appear as the description proceeds, the novel features thereof being pointed out in the appended claims.

For a full understanding of the invention, reference is to be had to the following description and accompanying drawings, in 45 which:—

Figure 1 is a front elevation of an airship which is provided with a safety attachment constructed in accordance with the invention, the safety attachment being shown 50 in inoperative position and the body of the airship appearing in section.

Fig. 2 is a top plan view of a portion of one of the upper supporting planes of the airship, showing the parachute as collapsed 55 and folded in the recessed portion of the plane, the closing flap of the recess being

swung upwardly and portions being broken away to illustrate the details of construction more clearly.

Fig. 3 is a longitudinal sectional view 60 through the portion of the supporting plane which is provided with the recessed portion in which the parachute is folded when collapsed, portions being broken away.

Fig. 4 is an elevation of one of the parachutes when swung upwardly and expanded into operative position, portions being broken away and shown in section to illustrate more clearly the details of construction. 70

Fig. 5 is an enlarged detail view of the hinged joint at the lower end of the parachute handle and the spring for swinging the parachute upwardly as soon as released. 75

Fig. 6 is a sectional view through the intermediate portion of the upper supporting plane, showing the releasing lever and associated mechanism for simultaneously releasing the two parachutes and the covering flaps of the recesses in which the parachutes 80 are housed when it is desired to bring the parachutes into operative position. 80

Fig. 7 is a detached perspective view of the releasing lever and sliding rods associated therewith, portions being broken away. 85

Fig. 8 is an enlarged detail view of one of the hook members for engaging the eyelets in the free edge of the covering flap for the recessed portion of the plane to normally hold the flap in a closed position. 90

Fig. 9 is a detail view of one of the U-shaped clips for engaging the swinging ends of the parachutes to hold the parachutes in a lowered position. 95

Corresponding and like parts are referred to in the following description and indicated in all the views of the drawings by the same reference characters.

For the purpose of illustration the invention is shown as applied to an aeroplane A 100 which is of the conventional construction, the supporting planes being formed in the usual manner of frames having fabric coverings stretched over the upper and lower surfaces thereof. The upper supporting plane 1 has the opposite end portions thereof recessed to receive elongated housings 2 which open through the top of the plane and are normally closed by the fabric flaps 3. These flaps 3 are shown as permanently secured by stitching 4 at one of their edges, and as provided at their free edges with 105 110

eyelets 5 which are releasably engaged by hooks 6 to hold the covering flaps normally in a closed position. The parachutes B when in a collapsed condition are folded 5 within the housings 2 and covered by the flaps 3, so that they do not increase the air resistance of the craft and the upper and lower surfaces of the supporting planes are substantially smooth and free from projecting members so that the lifting power of the 10 planes is not diminished in any manner.

Each of the parachutes B is formed with a handle 7 which is fitted at its lower end in a sleeve 8, said sleeve being formed with an 15 ear 9 which is connected by a pivot pin 10 to an arm 11 projecting from a ball 12 which is loosely fitted within a socket 13. These sockets may be formed in complementary sections or halves to facilitate the 20 assembling thereof in engagement with the balls 12, and suitable fastening means 14 is provided for securing the sockets to the bottoms of the housings 2 at the outer ends thereof. The pivot pin 10 is shown as projecting laterally upon opposite sides of the arm 11 and as having a spiral spring 15 fitted thereon, said spring normally tending to swing the handle 7 of the parachute into an upright position.

30 The fabric cover 16 of each of the parachutes B is shown as carried by ribs 17 which are connected by rods 18 to a ferrule 19, said ferrule being slidable upon the handle and the movements thereof controlling 35 the opening and closing of the parachute in the well-known manner. A coil spring 20 which is interposed between the ferrule 19 and a set collar 21 on the handle normally tends to slide the ferrule 19 upwardly and 40 open the parachute, and in order to collapse the parachute it is necessary to move the ferrule 19 downwardly against the action of the spring. This ferrule is shown as provided with a flange 22 which is engaged by 45 a detent 23 at the end of a spring arm 24 to lock the parachute in a collapsed condition when it is folded in the recessed portion or housing of the plane. This spring arm 24 is secured to the bottom of the housing 2 and 50 retains the detent 23 in engagement with the flange 22 of the ferrule until after the parachute has been swung upwardly and raised out of the housing. The parachute is thus prevented from flying open before it has 55 been raised a sufficient amount for the ribs thereof to clear the upper surface of the plane of the airship when the parachute opens up.

When the two parachutes are collapsed 60 they are folded downwardly into the respective housings 2, the handles thereof swinging upon the pivot pins 10 and bringing the springs 15 under tension. At the same time the detents 23 of the spring arms 24 are 65 brought into engagement with the flanges 22

of the ferrules 19, thereby locking the parachutes in a folded condition. The swinging ends of the collapsed parachutes are engaged by U-shaped clips 25 which straddle the same, the arms of the clips extending 70 through openings 26 in the lower surface of the plane and terminating in eyes 27. These eyes 27 are engaged by forks 28 carried by rods 29 which extend in opposite directions from a releasing lever 30, being secured 75 thereto on opposite sides of the pivotal support 31 for the lever. These rods 29 also carry slides 32 which extend through the respective end portions of the plane 1 at the sides of the housings 2, and from which the 80 before mentioned hook members 6 project, said hook members extending upwardly through eyelets 33 in the upper fabric covering of the plane so that they can be moved into and out of engagement with the eyelets 85 5 of the covering flaps 3. The releasing lever 30 is pivotally mounted upon a suitable supporting bracket 34 at the middle portion of the upper plane 1 and extends downwardly to a position within easy reach of an 90 aviator positioned in the body portion 35 of the airship. Under normal conditions the parachutes are collapsed and folded within the housings 2, being locked in a folded position by the U-shaped clips 25 which are engaged by the forks 28 of the rods 29. The covering flaps 3 are at this time stretched over the open upper sides of the housings 2 and held securely in operative position by engagement of the hooks 6 with the eyelets 95 100 5 of the flaps. In the event of a mishap or accident, the aviator has merely to grasp the releasing lever 30 and swing the same. This will result in simultaneously pulling inwardly upon the rods 29 and thereby moving the forked arms 28 out of engagement with the clips 25 and releasing the hooks 6 from the eyelets 5. The covering flaps 3 are thus free to swing upwardly and do not interfere with the upward movement and expanding of the parachutes B. The springs 15 will operate as previously described to swing the parachutes upwardly, and the detents 23 at the ends of the spring arms 24 will retain the parachutes in a collapsed condition until they have been moved out of the housings 2 and swung upwardly a sufficient amount so that they can be expanded without danger of the ribs striking upon the plane and possibly being damaged thereby. 110 115 As soon as the parachutes are in an upright position and expanded, they will provide a support for the airship and cause it to descend slightly to earth so that a landing can be made without loss of life. 120

Having thus described the invention, what I claim as new and desire to secure by Letters Patent, is:—

1. A parachute attachment for airships, including a collapsible parachute formed 130

- with a handle and having a ferrule slideable upon the handle to control the opening and closing of the parachute, means for loosely connecting the handle to the airship where-
5 by the parachute can be folded against the airship when not in use, a spring arm pro-
jecting from the airship and provided with a detent which engages the ferrule to lock the parachute in a collapsed condition when
10 it is folded against the airship, said detent remaining in engagement with the ferrule until the handle is partially swung upwardly, means for locking the parachute in a folded position, and means for releasing
15 the parachute.
2. A parachute attachment for airships, including a collapsible parachute formed with a handle, a pivot ear at the lower end of the handle, a ball provided with a short
20 arm, a pivot pin connecting the short arm to the ear, a spring applied to the pivot pin and normally tending to swing the handle upwardly, a socket loosely engaging the ball and applied to the airship, means for locking
25 the parachute in a folded position against the airship, and means for releasing the parachute.
3. The combination with an aeroplane having a recessed supporting plane, a cover-
30 ing flap for the recess, a collapsible para-
chute housed within the recess, means nor-
mally tending to move the parachute into
operative position, a slide provided with re-
35 taining elements adapted to engage the cov-
ering flap to hold it in a closed position,
means including a slide for locking the
parachute in the recess, and means for sim-
40 ultaneously moving the two slides to release
the parachute and covering flap.
4. The combination with an aeroplane formed with a recessed supporting plane, a covering flap extending across the mouth of the recess and having eyelets in the edge thereof, a slide provided with hooked arms
45 which releasably engage the eyelets, a col-
lapsible parachute housed within the recess,
means normally tending to move the para-

chute into operative position, locking means including a slide for holding the parachute in a folded condition, and a releasing ele- 50
ment operatively connected to both of the slides for simultaneously releasing the para-
chute and cover flap.

5. The combination with an aeroplane having a recessed supporting plane, of a 55 cover flap extending across the mouth of the recess, a slide provided with means for releasably engaging the cover flap to hold it in a closed position, a collapsible para-
chute folded downwardly in the recess, 60 means normally tending to swing the para-
chute upwardly into operative position, a
clip engaging the swinging end of the para-
chute and terminating in eyes which project
downwardly through the plane, a forked ele- 65
ment slidably engaging the eyes, and a re-
leasing member operatively connected to the
forked element and slide for simultaneously
releasing the clip and cover flap.

6. The combination with an aeroplane 70 having a recessed supporting plane, of a cover flap for the recess, a slide provided with means for releasably engaging the cover flap, a collapsible parachute adapted to be swung downwardly into the recess, 75 means normally tending to swing the para-
chute upwardly into operative position, a clip engaging the swinging end of the para-
chute and terminating in eyes which project
downwardly through the plane, a forked ele- 80
ment engaging the eyes, a releasing lever,
and a rod connected to the releasing lever
and carrying both the forked element and
the slide whereby the parachute and cover
85 flap are simultaneously released when the lever is operated.

In testimony whereof I have signed my name to this specification in the presence of two subscribing witnesses.

JOHN HARVEY HALL.
